Frank H. Harvey, INVENTOR:

By E. O. Brownman,
his Attorney.

UNITED STATES PATENT OFFICE.

FRANK H. HARVEY, OF DORRANCE, KANSAS.

SELF-FILLING FOUNTAIN-PEN.

1,027,127.

Specification of Letters Patent. Patented May 21, 1912.

Application filed May 18, 1911. Serial No. 627,900.

To all whom it may concern:

Be it known that I, FRANK H. HARVEY, a citizen of the United States, residing at Dorrance, in the county of Russell and State 5 of Kansas, have invented certain new and useful Improvements in Self-Filling Fountain-Pens, of which the following is a specification, reference being had therein to the accompanying drawing.

10 This invention relates to fountain pens, and has for its object to provide an improved fountain pen so constructed and arranged that it may be readily filled with ink.

15 The invention further has for its object to provide an improved fountain pen so constructed and arranged that it may be easily and readily taken apart for cleaning and will not be liable to get out of order.

20 Referring to the accompanying drawings:—Figure 1 is a view in elevation of a fountain pen constructed in accordance with this invention. Fig. 2 is a view of the pen in longitudinal section. Fig. 3 is a view of the pen in cross section on the line 3—3, 25 Fig. 2. Fig. 4 is a view in cross section on the line 4—4, Fig. 2. Fig. 5 is a detail view in longitudinal section of the upper end of the pen.

25 The fountain pen constructed in accordance with this invention is formed of several sections comprising the tapering pen holding end 1 and tubular section 2 connected to the tapering end 1 by means of a screw threaded projection 3 on the tapering end 1 which engages the threaded lower end of the tubular section 2. The pen further consists of a tubular section 4 connected at one end to one end of the tubular section 2 by a screw-threaded joint 5, the other end of the tubular section 4 being closed. Mounted in 40 the casing formed of these tubular sections is a piston 6 having a piston rod 7 which is detachably connected at its upper end by a reduced threaded projection 8 with an internally threaded cap 9 having a lateral projection 10 projecting through a slot 11 in the section 4 and on the outer end of which is mounted a strip 12 with a manipulating

head 13, the strip 12 being slidably mounted in a groove 14 in one side of the sections 50 2 and 4. As shown in Figs. 2 and 5 the slot 11 is of such a length as to limit the downward movement of the strip 12 and prevent the piston 6 from being moved above the lower end of the slot 11. 55

It will be seen that by means of this device that the casing 2 of the pen may be supplied with ink by dipping the pointed end of the pen in the ink and taking hold of the head 13 of the strip 12 and moving the latter along the groove 14 until it is brought in contact with the upper end of said groove. By constructing the casing of the pen in sections as hereinbefore described, not only can access be readily had to the casing to 60 clean the same but also the piston and piston rod may be readily inserted therein and removed therefrom. This is accomplished by unscrewing the sections and drawing the strip 12 out of the groove 14. 65

70 The fountain pen constructed in accordance with this invention is simple in construction and can be readily taken apart and put together, and filled with ink.

75 What I claim is:—

A fountain pen formed with a tapering pen holding member, a tubular section detachably connected with said member, a second tubular section detachably connected to said tubular section and having a slot in its side, a groove extending longitudinally in the side of the adjacent ends of said tubular sections and in alignment with said slot, a strip slidably mounted in said groove, a piston and piston rod located in the casing 80 of said pen, and a detachable lateral projection at one end of said piston rod projecting through said slot and connected to said slidable strip. 85

In testimony whereof I hereunto affix my 90 signature in presence of two witnesses.

FRANK H. HARVEY.
